Primary Examiner — Kendra Leslie Hamilton*Assistant Examiner* — Elizabeth S Struble(74) *Attorney, Agent, or Firm* — Baker, Donelson, Bearman, Caldwell & Berkowitz, PC; Aaron Chaloner; Ed Lanquist, Jr.(57) **CLAIM**

The ornamental design for a padding for a cervical collar, as shown and described.

DESCRIPTION

FIG. 1 is a rear view of a design of a padding for a cervical collar.

FIG. 2 is a front view of a design of a padding for a cervical collar.

FIG. 3 is a side view of a design of a padding for a cervical collar.

FIG. 4 is a rear perspective view of a design of a padding for a cervical collar; and,

FIG. 5 is a front perspective view of a design of a padding for a cervical collar.
